(57) CLAIM

The ornamental design for a vaporizer cartridge, as shown and described.

DESCRIPTION

FIG. 1 is a front-top perspective view of a vaporizer cartridge showing my new design.

FIG. 2 is a front-bottom perspective view showing my new design.

FIG. 3 is a front perspective view thereof.

FIG. 4 is a back perspective view thereof.

FIG. 5 is a left perspective view thereof.

FIG. 6 is a right side view thereof.

FIG. 7 is a top view thereof.

FIG. 8 is a bottom view thereof; and,

FIG. 9 shows the vaporizer cartridge in an environment of use.

The broken lines in the drawings depict portions of the vaporizer cartridge that form no part of the claimed design. The broken lines shown in FIG. 9 illustrate environmental subject matter only and forms no part of the claimed design.
